ATTORNEY.

UNITED STATES PATENT OFFICE.

ALBERT L. ROWLAND, OF BRAintree, MASSACHUSETTS, ASSIGNEE TO ASHTON HAM-
MER, OF BROCKTON, MASSACHUSETTS.

UNEXAMINED SEARCH.

Application filed May 7, 1926. Serial No. 107,872.

This invention relates to a finishing strip or welt for upholstery especially adapted among other uses to be employed as a filler member for a metal molding employed on automobile tops and other articles to be trimmed.

The invention has for its object to provide a simple, inexpensive, durable and efficient finishing strip, which can be made from thin material with a minimum number of layers, which can be manufactured at a minimum cost, and which is of sufficient stiffness to permit it to be arched transversely and to maintain its shape when in operative position in the molding.

The particular features of the invention will be pointed out in the claims at the end of this specification.

Fig. 1 is a side elevation of a metal molding provided with a filler member embodying this invention;

Fig. 2, a section on the line 2—2, Fig. 1;

Fig. 3, a perspective view of a portion of the finishing strip in an unfolded condition;

Fig. 4, a perspective of the finishing strip folded longitudinally from the condition illustrated in Fig. 3, and

Fig. 5, a section of another form of metal molding with the filler member or finishing strip inserted therein.

Referring to the drawing, *a* represents a finishing strip embodying this invention, and *b*, a metal molding with which the finishing strip is used as a filler member therefor.

The metal molding is provided with a back member 10 and with inwardly curved side flanges 12 forming channels 14, and spaced apart to leave a space 15 of substantial width which is closed by the finishing strip *a*.

The present invention has for its object to provide a finishing strip which is pleasing in appearance and of such simple construction as to enable the cost of the same to be reduced to a minimum so that it may be used on inexpensive automobiles, and yet is of such a construction as to maintain its shape after being inserted into the molding *b*.

To this end, the finishing strip is made from a strip or blank of cloth having on one surface a coating or covering of enamel or like finish. The cloth strip or blank is relatively thin and is made of sufficient width

to enable side portions thereof to be folded over and form side flaps 20, 21.

One of the side flaps as 20 is made wider than the other 21 and is separated therefrom by a space of substantial width which leaves uncovered a portion 22 of the main strip.

The main strip is folded longitudinally so that the uncoated surfaces of the side flaps are contiguous and these surfaces are secured together by a layer of cement, represented by the heavy black lines 23, 24 (see Fig. 3). The narrower side flap 21 is folded over a cord 25 preferably of paper for a purpose as will be described.

The uncovered portion 22 of the strip is then folded longitudinally to form one edge 26 of the main portion of the finishing strip, the other edge 27 of which is formed by the folded side flap 20.

The parts of the uncovered portion 22 formed by folding the latter longitudinally are firmly secured together by cement, which is represented by the heavy black line 28 in Figs. 2 and 4.

The uncovered portion 22 of the strip is folded longitudinally so that the bead formed by the side flap 21 and cord 25, will be positioned at or near the longitudinal center of the main member of the finishing strip, which member is composed of a transversely continuous outer layer 30 and an inner layer having a wide section formed by the flap 20, and a narrow section 32, which sections are secured to the outer layer 30 by the cement layers 23, 24, which cement layers reinforce the outer and inner layers to such extent as to enable the main portion or member of the finishing strip to be curved or arched transversely and to retain such shape while possessing the desired flexibility to enable it to be quickly and easily inserted into and removed from the molding.

The beaded member of the finishing strip is composed of layers of unequal widths cemented together, with the wider layer attached to the narrower section 32 of the inner layer of the main member. The flap 21 constitutes the narrow section of the beaded member, and the wider section 32 has its beaded edge substantially at the transverse center of the outer layer 30 of the main member.

The beaded member co-operates with the

arched main member and with the back 10 of the metal molding to support the arched member substantially at the center of the arch, and thereby maintain the arched member in the desired condition to present an attractive, pleasing and finished appearance in the molding.

The beaded member is preferably arranged to engage the nails 40 employed to 10 secure the metal molding to the frame of the automobile top with which it is used.

From the above description, it will be seen that a finishing strip is provided which is free from stitches, which are objectionable in two respects when the finishing strip 15 is made of thin material, such as enameled cloth, in that they pucker the finishing strip and render its outer surface more or less rough and unsightly, and in that they deteriorate under the influence of the weather 20 and thereby shorten the life and usefulness of the finishing strip.

In the present instance, the layers 23, 28 of cement which unite the two layers forming the main or arched member of the finishing strip, serve to stiffen said member so that it will retain its curved or arched shape under conditions of use; enable the number of layers of material to be reduced 25 to the minimum, and reduce the cost of manufacture, which enables inexpensive or low cost automobiles to be provided with finishing strips which add to the finish and appearance of the same.

35 In Fig. 5, the molding b is shown as provided with a gutter 41 attached to the lower side flange 13.

What I claim is:

1. A finishing upholstery strip of the 40 character described, composed of a single piece of fibrous material folded longitudi-

nally to form a main member capable of being arched transversely and having a transversely continuous outer layer and an inner layer provided with a wide and a narrow section which co-operate with said outer layer to provide the finishing strip with side edges of substantially equal thickness, said wide section being cemented to 45 said outer layer, and a beaded member composed of layers of unequal width cemented together, the wider layer of the said beaded member being attached to the narrower section of the inner layer of said main member and having its bead located substantially at 50 the transverse center of the outer layer of said main member.

2. A finishing upholstery strip of the character described, composed of a single piece of fibrous material folded longitudinally to form a wide side flap and a narrow side flap separated by an uncovered portion of the strip, said uncovered portion being folded longitudinally between said side flaps to form a main member capable of being 55 arched transversely and having a continuous outer layer and an inner layer composed of the wide side flap and a part of the folded uncovered portion of the fibrous strip, which co-operate with the said outer 60 layer to provide the said main member with side edges of substantially the same thickness, and a beaded member composed of the narrow side flap and the other part of the folded uncovered portion of the fibrous 65 strip and having its bead located substantially at the transverse center of said main member.

In testimony whereof, I have signed my name to this specification.

ALBERT L. HOWARD.
